UNITED STATES PATENT OFFICE.

EDWARD POSSON, OF CHICAGO, ILLINOIS.

TIE-PLATE.

1,111,092.

Specification of Letters Patent. Patented Sept. 22, 1914.

Application filed September 21, 1911. Serial No. 650,517.

To all whom it may concern:

Be it known that I, EDWARD POSSON, a citizen of the United States, residing at Chicago, in the county of Cook and State of Illinois, have invented certain new and useful Improvements in Tie-Plates, of which the following is a specification.

The object of my invention, generally stated, is to provide an improved tie plate 10 adapted to be applied to the ties at the mill where the ties are prepared, and adapted to be constructed of rolled metal subsequently shaped by suitable dies to the required form. It will be obvious, however, 15 that the improved form of tie plate herein described may be made of other materials or by other methods, and that it may, if desired, be secured to the ties after they are delivered from the mill.

20 The objects of the invention will more clearly appear from the following description and drawings, in which—

Figure 1 is a transverse view, partially in section, showing one form of my tie plate 25 with a rail in place thereon. Fig. 2 is a plan view of the structure shown in Fig. 1. Fig. 3 is a side view of the structure shown in Fig. 1. Fig. 4 is a perspective view of the tie plate illustrated in Fig. 1, the same 30 being separated from the other parts of the structure. Fig. 5 is a perspective view of a wedge designed for use in connection with my tie plate. Fig. 6 is a perspective view 35 of a lock designed to hold the wedge in place, the lock being illustrated before its outer end is bent down to the position shown in Fig. 1. Fig. 7 is a view similar to Fig. 1, showing a transverse section through a modified form of tie plate; and Fig. 8 is a 40 perspective view of the tie plate shown in Fig. 7 separated from the other parts of the structure.

While I will describe my tie plate as being formed from a section of a strip of 45 rolled metal, it will be understood, as above stated, that the invention is not necessarily confined to such mode of construction. In the section of rolled metal 1 which constitutes the body of the tie plate, openings 2 50 are punched or otherwise formed for the reception of the spikes, whereby it is held to the tie. The upwardly projecting lugs 3 are also formed by punching the same from the section of rolled metal 1, the lugs

being separated from the body of the tie 55 plate upon three sides and bent upwardly at the fourth side. Each of the upwardly projecting lugs in the form of the device illustrated in Fig. 1 is provided with an aperture 4 extending therethrough in a direction transverse of the rail 5, which is designed to rest upon the tie plate between the lugs 3.

In order to hold the rail in place, I provide wedges 6 designed to be inserted 65 through the apertures 4 in a direction transverse of the rail. Each of the wedges is provided with an inclined surface 7, designed to conform to the upper surface of the rail base 8, and is further provided with 70 a downwardly projecting lug 9 designed to rest upon the main body or base plate of the structure.

For the purpose of holding the wedge in its home position, I use preferably the locking device 10 shown in detail in Fig. 6, which illustrates the lock in its initial condition. At its inner end, that is, the end designed to lie adjacent the rail, the lock 10 is provided with an upwardly projecting 80 lug 11, designed to rest against the inner face of the lug 3, as shown in Fig. 1. At a distance from the lug 11 equal to the thickness of the lug 3, the lock 10 is provided with outwardly projecting shoulders 12 designed to rest against the outer surface of 85 the lug 3.

In assembling the structure the rail 5 is placed upon the tie plate, as shown in Fig. 1. One of the locks 10 is then placed in 90 position against the upper side of the opening 4 in the lug 3 with its lug 11 resting against the inner face of the lug 3, and its lugs 12 against the outer face of the lug 3. At this time the outer end 13 of the lock 95 10 extends straight outwardly, as indicated in dotted lines in Fig. 1. The wedge 6 is then inserted in place and driven home, thereby causing a firm wedging contact between the surface 7 of the wedge and the 100 upper surface of the rail base 8. After the wedge 6 is driven home, the outer end 13 of the lug 10 is bent downwardly to the position indicated in full lines in Fig. 1, thereby firmly securing the wedge in position and 105 preventing any possibility of displacement. The shoulders 12 upon the lock 10 serve to hold said lock against inward movement

when the wedge 6 is driven to its home position.

In Fig. 1 I have illustrated the same arrangement upon both sides of the rail, both edges of the rail base being secured by means of wedges.

In Fig. 7 I have shown a modification, in which the left side of the rail base is held in position by means similar to those above described in connection with Fig. 4. In this form, however, I employ an integral lug 14 upon the opposite side of the rail base, this integral lug being formed by bending upwardly and inwardly a part of the base plate of the structure.

In the initial assemblage of the parts, the tie plates are spiked to each tie at such distances apart that when the rails are separated to the utmost limit permitted by the outer lugs 3 upon the two tie plates, the proper rail gage will be secured. Referring to Fig. 1, the letter *a* indicates the inner side of the rail head, that is, the side toward the center of the track. It will be observed that the outer edge *b* of the rail base lies in contact with the outer lug 3. As above stated, the tie plates are so spaced upon the ties that when a new rail is mounted upon the tie plates with its outer edge *b* in contact with the outer lug, the proper gage will result. As the rail head becomes worn from use, and it becomes necessary to set the rails closer together in order to restore the proper gage, the rail is moved inward, that is, to the left, as illustrated in Fig. 1, and a piece of metal or shim 20 is introduced between the edge *b* of the rail base and the lug 3. The wedge 6 at the left is then driven home and locked in place, thereby forcing the rail against the shim and the shim against the right hand lug 3. The wedge 6 at the right is then driven home, thus leaving the rail in its new adjustment. The lugs 3 upon the tie plates are spaced apart sufficiently to permit the maximum adjustment for wear ordinarily needed. As will be noted upon reference to Fig. 1, I have shown a clearance space at *c*, this space representing the amount which the distance between the lugs exceeds the width of the base rail. Ordinarily an eighth of an inch clearance will permit the adjustment necessary for taking up wear and restoring the standard gage.

In the assembled structure it will be noted that the rails lie over the apertures formed by bending the lugs upwardly. The downward pressure of the wedges on the rail base tends to slightly depress the base of the rail into the aperture formed by displacing the lug, thus effecting a slight depression which has a tendency to prevent the rail from creeping.

What I claim is—

1. A device of the class described com-

prising a base plate adapted to support a rail, upwardly projecting lugs adapted to lie at opposite sides of said rail, a wedge adapted to pass through an aperture in one of said lugs and having an inclined lower surface adapted to engage the rail base, and a lock having shoulders engaging the outer end of said wedge and the inner and outer sides of said lug.

2. A device of the class described comprising a base plate having lugs projecting from the upper side thereof, said base plate being adapted to support a rail between said lugs, one of said lugs projecting upwardly and inwardly to conform to the base of said rail, and the other lug having an aperture extending therethrough transversely of said rail, a wedge adapted to pass through said aperture and engage the base of said rail, and a lock having shoulders engaging the outer end of said wedge and the inner and outer sides of said lug.

3. A tie plate comprising a base formed of rolled metal and adapted to support a rail, integral lugs connected with said base at one edge and formed by severing the other edges from said base plate and bending said lugs upwardly on the connected edge, said lugs being perforated and adapted to lie at opposite sides of said rail, and wedges adapted to pass through the perforations and having inclined lower surfaces to engage the rail base.

4. A tie plate comprising a base formed of rolled metal and adapted to support a rail, integral lugs connected with said base at one edge and formed by severing the other edges from said base plate and bending said lugs upwardly on the connected edge, said lugs being perforated and spaced apart a distance greater than the width of the rail base, wedges adapted to pass through the perforations and having inclined lower surfaces to engage the rail base, and a shim to position said rail between said lugs.

5. A device of the class described comprising a base plate to support a rail, upwardly projecting lugs adapted to lie at opposite sides of a rail, wedges adapted to pass through apertures on said lugs and having inclined surfaces to engage the rail base, and a lock engaging the inner face of said lug and the outer end of said wedge.

6. A device of the class described comprising a base plate to support a rail, upwardly projecting lugs adapted to lie at opposite sides of a rail, wedges adapted to pass through apertures in said lugs and having inclined surfaces to engage the rail base, and a lock engaging the inner face of said lug and bent down over the outer end of said wedge.

7. In a device of the class described, a tie plate comprising a base formed of rolled

metal, integral lugs connected with said base at one edge and formed by severing the other edges from said base plate and bending said lugs upwardly on the connected edge,

5 a rail resting on said base over the apertures formed by bending upwardly the material of said lugs, said lugs being perforated, and wedges passing through the per-

forations in said lugs and engaging the base of said rail

In testimony whereof, I have subscribed my name.

EDWARD POSSON.
